DESIGN FOR AN OIL BURNER

Emert J. Lattner, Cedar Rapids, Iowa

Application October 17, 1936, Serial No. 65,332

Term of patent 7 years

To all whom it may concern:

Be it known that I, Emert J. Lattner, a citizen of the United States, residing at Cedar Rapids, in the county of Linn and State of Iowa, have invented a new, original, and ornamental Design for Oil Burners, of which the following is a specification, reference being had to the accompanying drawing, forming part thereof.

I claim:

The ornamental design for an oil burner, as shown and described.

EMERT J. LATTNER.
